UNITED STATES PATENT OFFICE.

THOMAS SMITH, OF CUMBERLAND, MARYLAND.

DESIGN FOR A SEWER-TRAP.

44,422.

Specification for Design.

Patented July 29, 1913.

Application filed May 15, 1913. Serial No. 767,926. Term of patent 14 years.

To all whom it may concern:

Be it known that I, THOMAS SMITH, a citizen of the United States, residing at Cumberland, in the county of Allegany and State of Maryland, have invented a new, original, and ornamental Design for Sewer-Traps, of which the following is a specification, reference being had to the accompanying drawing, forming part thereof.

The figure is an elevation of the sewer trap, showing my new design.

I claim:

The ornamental design for a sewer trap, as shown.

THOMAS SMITH.
